Primary Examiner — Caron D Veynar*Assistant Examiner* — Martie K Holtje(74) *Attorney, Agent, or Firm* — Wood, Herron & Evans, LLP**CLAIM**

The ornamental design for a timer, as shown and described.

DESCRIPTION

FIG. 1 is a front perspective view of a timer showing our new design;

FIG. 2 is a front perspective view thereof similar to FIG. 1 with the numbers removed for clarity;

FIG. 3 is a front elevational view thereof;

FIG. 4 is a left elevational view thereof. The right elevational view is a mirror image thereof;

FIG. 5 is a rear view thereof;

FIG. 6 is a top plan view thereof; and,

FIG. 7 is a bottom plan view thereof.

The structural elements and numerals depicted by broken lines have been shown for the purpose of illustrating portions of the timer that form no part of the claimed design.
